(57) **CLAIM**

We claim the ornamental design for a bottle, as shown and described.

DESCRIPTION

FIG. 1 is a perspective view of a bottle showing our new design.

FIG. 2 is a front elevational view of the bottle in FIG. 1.

FIG. 3 is a rear elevational view of the bottle in FIGS. 1 and 2.

FIG. 4 is a side elevational view taken from the right side in FIG. 2.

FIG. 5 is a side elevational view taken from the left in FIG. 2; and,

FIG. 6 is a top plan view of the bottle in FIGS. 1-5.

The bottle of the present disclosure is characterized by circular features on the inside surfaces of the body and shoulder. Dash-dash-dash broken lines shown in the drawings represent environmental structure and are not part of the claimed design.

Dash-dot-dash broken lines shown in the drawings represent boundaries of the claimed design and are not part of the claimed design.
